UNITED STATES PATENT OFFICE

GEORGE THOMAS FIELDING, OF STAMFORD, CONNECTICUT

DISHWASHING APPARATUS

Application filed October 20, 1930. Serial No. 490,028.

This invention relates generally to apparatus for cleansing various articles by scrubbing and rinsing operations, and comprehends a device which, while not necessarily restricted to such use, is particularly designed for washing tableware or culinary implements.

Broadly, the invention aims to provide a device of the indicated character, by virtue of which scrubbing with a liquid cleansing solution and rinsing of the articles being cleansed, may be rapidly, thoroughly and effectually accomplished.

The invention further resides in the provision of an improved device of this class, which embodies scrubbing and rinsing means so related that the removal of the articles from the scrubbing means exposes them automatically to the action of the rinsing means.

More specifically, the invention contemplates an improved device for washing and rinsing dishes or analogous articles, which essentially embodies a pair of contiguous parallel rotary scrubbing elements between which the articles are passed, together with means for projecting a rinsing spray onto the surfaces of said articles as they are removed from between the scrubbing elements.

The invention furthermore resides in the provision of a washing and rinsing device equipped with means for mixing and supplying a cleansing medium to the scrubbing elements.

The invention further aims to provide means for removably mounting and associating the scrubbing elements with the device so that they may be removed and replaced when worn.

As a still further object, the invention comprehends a device of the character set forth which employs few and simple parts capable of economical production and assembly, to afford a compact and durable structure which is highly efficient in its purpose.

With the above recited and other objects in view, reference is had to the following description and accompanying drawings, in which there is exhibited one example or embodiment of the invention, while the claims define the actual scope of the same.

In the drawings:

Figure 1 is a perspective view of the device.
Figure 2 is a plan view thereof.

Figure 3 is a transverse sectional view therethrough taken approximately on the line 55 indicated at 3-3 in Figure 2.

Figure 4 is a similar view taken approximately on the line 4-4 of Figure 2.

Figure 5 is a fragmentary sectional view taken approximately on the line 5-5 of 60 Figure 4.

Figure 6 is a fragmentary sectional view taken approximately on the line 6-6 of Figure 2.

Referring to the drawings by characters of 65 reference, 10 designates a base provided at one end with a water tight casing or housing 11 and at the opposite end with a pair of laterally spaced upstanding brackets 12. The casing 11 houses an electric motor 13, the 70 shaft 14 of which has secured thereto a worm 15 which meshes with a worm pinion 16 on a stub shaft 17. The stub shaft has secured thereto a gear pinion 18 which meshes with and is designed to drive one of a pair of 75 meshed gears 19 and 20 the shafts 21 and 22 of which are journaled in the inner wall 23 of the casing or housing 11, and which shafts 21 and 22 extend through and project from the wall 23 and are provided with tubular 80 exteriorly disposed extremities 24 and 25. The extension cord 26 leads from the motor within the casing or housing 11 and is provided with the usual form of attachment plug 85 27 for plugging into a source of supply to drive the motor and gear train.

A pair of rotary cylindrical brushes designated generally by the reference characters A and B is provided, and said brushes each include a shaft 30. Each shaft is provided with a substantially cylindrical major set of radial bristles 31 and an axially spaced minor set of bristles 32 at one end of the shaft, the latter being arranged to form brushes having substantially semi-spherical ends. The portions of the shafts 30 which are exposed between the bristle sets are removably mounted in bearings 33 provided at the upper ends of the brackets 12, and, if desired, retaining pins 34 are associated with the bearings 33 to pre- 95 100

vent accidental displacement of the shafts from the bearings. The ends of the shafts 30 opposite to the ones which carry the set of bristles 32 are designed to removably fit within the tubular extremities 24 and 25 of the gear shafts 21 and 22, and a suitable coupling therebetween is established to cause the brushes A and B to be driven by the motor and gear train in the direction indicated by the arrows. This coupling may consist of a bayonet slot in each of the extremities 24 and 25 and co-operating pins in each of the shafts 30. This provides a pair of rotary parallel contiguous scrubbing brushes or elements A and B, between which the articles such as plates, saucers, pans or the like, may be passed to subject the same to a scrubbing action, while cups, bowls, tumblers or the like may be positioned over the bristle sets 32 at the ends of the brushes A and B. The brackets 12 are also provided with supporting arms 35 and 36, which support a pair of spray pipes 37 and 38 respectively disposed over and parallel to the brushes A and B. These spray pipes, 37 and 38, are arranged as shown, in order to direct the flow of a fluid, such as clear water direct from the supply, toward the brushes and from opposite directions so that the sprays meet on a line on the tangential plane between and common to the brushes to cause the fluid to spray substantially tangentially upon the brushes at and adjacent their contiguous peripheral portions substantially in the direction of movement of the brushes. The spray pipes are respectively connected at one end with a common intake 39 which leads from the outlet 40 of a three-way valve casing 41, which is also provided with an upwardly directed outlet 42 having a spray head 43. A rotary valve core 44 is mounted within the casing for selectively directing water from its inlet 45 to the outlet 40 or simultaneously to the outlets 40 and 42. The inlet 45 of the valve casing joins a T-coupling 46, and one branch of the T-coupling is connected with a flexible conduit 47 which leads to a water supply, such as a faucet, a faucet engaging nipple 48 being provided at the free extremity thereof. The remaining branch 49 of the T-coupling leads to and extends through the cover 50 of a mixing vessel 51 which contains a cleansing substance with which the water supply to the vessel is adapted to be mixed and the solution discharged through an outlet conduit 52 extending through the cover 50 and communicating with a discharge pipe 53 which is supported by the bracket arm 36, the discharge pipe 53 extending alongside of and parallel to the brush B below the spray pipe 38.

In use and operation, the device is placed in a sink, the conduit attached to the faucet and the attachment plug insert in an outlet. With the brushes A and B rotating in the directions indicated by the arrows and the

water flowing from the faucet, it is apparent that a soapy solution will be supplied directly to the brush B and indirectly to the brush A, while a clear rinsing water will be supplied to the spray pipes 37 and 38 and the spray head 43 if the valve core 44 is turned to permit. The plates, saucers, pans or other articles of this character are passed between the rotating bristle sets 31 of the brushes A and B downwardly to permit the bristles to act thereupon, together with the soapy cleansing water, and are thence drawn upwardly, thus insuring the removal of all foreign matter from the surfaces thereof. As the articles are withdrawn upwardly from between the bristle sets 31, they will be acted upon by the water sprayed from the spray pipes 37 and 38, to rinse off the soapy solution. It will thus be seen that in one operation the articles are thoroughly cleansed and rinsed and the water sprayed from the spray pipes 37 and 38 being sprayed over and between the brushes will wash and cleanse the brushes of matter gathered thereon from the articles.

The bowls, cups, tumblers or other similar articles are positioned over the bristle sets 32 to act upon both the interior and exterior surfaces thereof, the soapy solution from the pipe 53 being supplied to the bristle sets 32. After the washing of these articles, the spray head 43 may be employed for rinsing the same.

It is to be understood that no limitation is necessarily made to the precise structural details, but that variations and modifications which properly fall within the scope of the claims may be resorted to when desired.

What is claimed is:

1. A dish-washing device having the combination of a pair of rotary scrubbing brushes mounted horizontally in substantially the same plane upon parallel axes with the peripheries of said brushes in contiguous relation and between which the articles to be cleansed are passed, means for rotating the left-hand brush of said pair in a clockwise direction and the right-hand brush of said pair in a counter-clockwise direction, means adjacent one of said brushes for applying a cleansing medium to the upper portion thereof, and means located above said brushes for spraying a fluid over and between the brushes for washing and cleansing the brushes and articles and for rinsing the articles as they are withdrawn from between the brushes.

2. A dish-washing device having the combination of a pair of rotary scrubbing brushes mounted horizontally in substantially the same plane upon parallel axes, said brushes having the peripheries thereof in contiguous relation and between which the articles to be cleansed are passed, means for driving said brushes, said means including gear mechanism constructed and arranged to rotate the left-hand brush of said pair in a clockwise direction and the right-hand brush in a counter-clockwise direction, means adjacent one of said brushes for applying a cleansing medium to the upper portion thereof, and means located above said brushes for spraying a fluid over and between the brushes for washing and cleansing the brushes and articles and for rinsing the articles as they are withdrawn from between the brushes.

direction and the right-hand brush of said pair in a counter-clockwise direction, means including a perforated tubular member adjacent one of said brushes and parallel thereto for applying a cleansing medium to the upper portions thereof substantially throughout its length, and means including a pair of spaced horizontal perforated tubular members located in a plane above said last mentioned means for spraying a rinsing liquid onto the opposite surfaces of the articles as they are withdrawn from between the brushes.

3. A dish washing device having the combination of a pair of rotary scrubbing brushes mounted in substantially the same plane upon parallel axes with the peripheries of said brushes in contiguous relation between which the articles to be cleansed are passed, means for rotating the brushes in opposite directions, means for spraying a rinsing fluid upon the articles as they are withdrawn from between the brushes, said means including a pair of spray elements having confronting faces, said spray elements being spaced apart from each other and the brushes and having openings in the confronting faces thereof to direct the fluid from the spray elements toward the brushes and in opposite directions to meet on a line on the tangential plane between and common to both brushes to cause the fluid to spray substantially tangentially upon the brushes substantially in the direction of movement of said brushes at and adjacent the contiguous peripheral portions thereof.

40 4. A dish washing device having the combination of a pair of rotary scrubbing brushes mounted in substantially the same plane upon parallel axes with the peripheries of said brushes in contiguous relation between which the articles to be cleansed are passed, means for rotating the brushes in opposite directions, and means for spraying a rinsing fluid upon the articles as they are withdrawn from between the brushes, said means including a pair of spray elements having confronting faces, said spray elements being spaced apart from each other and the brushes and having openings in the confronting faces thereof to direct the fluid from the spray elements in opposite directions to meet on a line on the tangential plane between and common to both brushes.

45 5. A dish washing device having the combination of a pair of rotary scrubbing brushes mounted in substantially the same plane upon parallel axes with the peripheries of said brushes in contiguous relation between which the articles to be cleansed are passed, means for rotating the brushes in opposite directions, and means for spraying a rinsing fluid

upon the articles as they are withdrawn from between the brushes, said means including a pair of spray elements having confronting faces, said spray elements being spaced apart from each other and the brushes and having opening in the confronting faces thereof to direct the fluid from the spray elements toward the brushes and in opposite directions to meet on a line on the tangential plane between and common to both brushes to cause the fluid to spray substantially tangentially upon the brushes substantially in the direction of movement of said brushes at and adjacent the contiguous peripheral portions thereof.
